Primary Examiner — Sheryl Lane*Assistant Examiner* — Emily A Caven(74) *Attorney, Agent, or Firm* — Brian F. Russell(57) **CLAIM**

The ornamental design for a pet toy as shown and described.

DESCRIPTION

FIG. 1 is a top perspective view of the pet toy.

FIG. 2 is a front elevation view of the pet toy.

FIG. 3 is a back elevation view of the pet toy.

FIG. 4 is a top plan view of the pet toy.

FIG. 5 is a bottom plan view of the pet toy.

FIG. 6 is a left side elevation view of the pet toy; and,

FIG. 7 is a right side elevation view of the pet toy.

The dash-double-dot lines in the drawings form a boundary between claimed and unclaimed portions of the design. The regular dashed lines in the drawings illustrate portions of the pet toy forming no part of the claimed design.

1 Claim, 5 Drawing Sheets(56)
